UNITED STATES PATENT OFFICE.

ERIC H. LARSON, OF CHICAGO, ILLINOIS, ASSIGNOR TO THE LOGO-DIAL CORPORATION,
A CORPORATION OF ILLINOIS.

LOGGING DEVICE FOR RADIO TUNING INSTRUMENTS.

Application filed May 4, 1925. Serial No. 27,986.

My invention relates to improvements in logging devices for radio tuning instruments, and it consists in the combinations, constructions, and arrangements herein described and claimed.

An object of my invention is to provide a logging device of the character described which is adapted for disposition upon the rotor shaft of a variable condenser, variometer, or radio coupler employed in the ordinary radio circuit, and which takes the place of the dial ordinarily disposed upon the rotor shaft, and used for the purpose of turning the shaft to tune the instrument so as to tune in and select certain stations broadcasting. The device includes means for indicating just what station the instrument is set for, and provides a tape upon which inscriptions pertaining to the station may be inscribed, which inscriptions will be visible only at the time the device is actuated to turn the rotor shaft in the position for turning in at that particular station.

A further object of my invention is to provide a device of the type described in which the movement of the tape upon which the call letters pertaining to the stations desired have been logged is moved at a relatively high rate of speed, while the movement of the rotor shaft is relatively slow, thereby rendering great selectivity in tuning.

A further object of the invention is to provide a device of the type described in which the speed of rotation of the control knob is relatively faster than the speed of the rotor shaft, thereby rendering great accuracy in selecting the stations through rotation of the rotor shaft and consequently rotation of the tape.

A further object of the invention is to provide a device of the character described in which means is employed for maintaining the tape taut at all times so that there is no possibility of the tape shifting upon its reels or becoming slack and thus binding within the casing.

A further object of the invention is to provide a device of the type described in which auxiliary means associated directly with the rotor shaft is employed for indicating the degrees from a predetermined position that the rotor shaft is rotated, which in the ordinary type of radio circuit is limited to 180°.

A further object of the invention is to provide a logging device for radio tuning instruments which is simple in construction.

Other objects and advantages will appear in the following specification, and the novel features of the invention will be particularly pointed out in the appended claims.

My invention is illustrated in the accompanying drawings forming part of this application, in which

Figure 1 is a front elevation of an embodiment of the invention,

Figure 2 is a top plan view of the mechanism illustrated in Figure 1,

Figure 3 is a sectional view along the line 3—3 of Figure 2 with portions of the interior mechanism broken away, and

Figure 4 is a sectional view substantially along the line 4—4 of Figure 3.

In carrying out my invention I make use of the ordinary type of radio tuning instrument, such as a variable condenser, the external housing of which is shown in Figure 4 at 1. This condenser has a rotor shaft 2 which when turned moves certain instrumentalities within the chamber, thereby changing the capacity of the instrument and altering the internal wave length of the radio set of which the condenser or other instrument forms a part. The only portion of these tuning instruments which is important in so far as my present invention is concerned is the shaft 2.

My improved logging device consists in a metal casing 3 having a flat top wall 4 with a rectangular aperture 5 therethrough. The casing 1 has a gear 6 rotatably mounted therein which is provided with a hollow shaft 7. The rotor shaft 2 is projected within the hollow shaft 7 and keyed against movement thereto by means of a set screw 8 projected through a portion 9 of the shaft 7 which extends exteriorly of the casing 3. An indicating hand 10 extends radially from the portion 9 of the shaft 7 and an arcuate scale 11 of 180° is disposed upon the front face of the casing 3 in registration with the plane of the outer portion of the hand 10.

Means for operating the gear 6 slowly so as to rotate the rotor shaft 2 slowly is provided in a knob 12 carried by a shaft 13 which is rotatably mounted within the casing 3. A gear 22 is carried by the shaft 13

which is in mesh with the teeth of a larger gear 24 so that rotation of the shaft will cause slow rotation of the gear 24.

A pinion 14 is carried by the shaft of the gear 24 which pinion is in mesh with the gear 6. Thus rotation of the knob 12 will cause relatively slow rotation of the shaft 2 in the same direction.

A pair of hollow drums 15 and 16 are rotatably mounted by means of shafts 17 and 18 respectively within the casing 3. The drum 15 has a coiled spring 19 therein. This spring is secured at its innermost end to the adjacent shaft 17 and at its outermost end to the inner wall of the drum 15 so as to resist rotation of the drum in one direction and thereby tend to rotate the drum 15 in one direction when the spring is partially wound. A paper tape 20 is secured at opposite ends to the drums 15 and 16 respectively, and is wound upon the peripheral wall of the drums. This tape 20 is passed over a shoe 21 beneath the aperture 5 in the top wall 4 of the casing.

When one-half of the tape 20 is wound upon the drum 16, and the other half on the drum 15, the spring 19 is wound up substantially one-half of its capacity.

The gear wheel 24 is in mesh with a pinion 25 carried by the shaft 17 associated with the drum 16. A gear 26 is in mesh with the pinion 25 and in mesh with a pinion 27 carried by the shaft 18 associated with the drum 15. Thus rotation of the shaft 13 as by actuation of the knob 12 will cause the drums 15 and 16 to rotate in the same direction at a higher speed than the shaft 13 and thus move the tape 20 over the shoe 21.

The spring 19 serves to take up any slack which might otherwise occur between the drums, due to the constantly changing effective diameter of the drums and tape.

From the foregoing description of the various parts of the device the operation thereof may be readily understood. Let us assume that the rotor shaft 2 of the tuning instrument 1 is set so as to tune the radio receiver of which the instrument 1 is a part for receiving radio broadcasting signals from station WMAQ. The operator would then write the call letters of the station WMAQ on the tape 20 as it appears directly in the center of the aperture.

This station is then logged and the operator may at any time turn the knob 12 so as to cause the rotor shaft 2 to rotate and the tape 20 to move simultaneously to the position necessary to tune in station WMAQ, since movement of the tape 20 and the rotor shaft 2 is synchronized by virtue of the positive gear trains described. The legends WMAQ will always appear at the center of the aperture 5 when the shaft 2 is in the position to tune in WMAQ.

Let us assume now that it is desired to tune in another station which has a wave relatively close to the wave of the station WMAQ. Station KDKA may be such a station. Thus a slight movement of the rotor shaft 2 will set the instrument 1 for that station when the knob 12 is actuated to rotate the shaft 2 a slight degree. The tape 20, however, will travel relatively faster than the rotative movement of the shaft 2, i. e., the shafts 17 and 18 of the drums 15 and 16 respectively will rotate faster than the shaft 7 which is connected with the rotor shaft 2.

This will keep another portion of the tape 20 in registration with the central part of the aperture 5 and the legends KDKA may be marked upon the tape so that the operator at any time may reset the instrument 1 for that station.

One of the most important features of my invention consists in the mechanism for moving the tape 20 at a relatively high speed relative to the rotation of the shaft 2, so that there is ample room for the disposition of legends upon the tape. Accurate tuning of the stations is made possible by the reduced speed between the knob 12 and the shaft 2.

The relative position of the shaft 2 is at all times indicated by the shaft on the scale 11.

I claim:

1. The combination with a rotor shaft, of a casing, a gear disposed within said casing and adapted for engagement with said rotor shaft, a manually actuated pinion in mesh with said gear for slowly rotating said rotor shaft, a pair of drums rotatably mounted within said casing, a tape having its opposite ends secured to said drums and being wound upon said drums, whereby rotation of said drums in the same direction will cause the tape to pass from one drum to the other, said casing having an aperture therethrough through which the tape may be observed, a spring for resisting rotation of said drums in one direction, and gears connecting said drums with the shaft of said manually actuated pinion, whereby the operation of said manually actuated pinion will cause the rotation of said drums at a relatively high rate of speed.

2. The combination with a rotatable control shaft, of a casing having an aperture therethrough, a movable tape disposed within the casing and arranged for movement with respect to said aperture, a control knob, means for turning said shaft when said control knob is turned at a speed less than the control knob, and other means operatively connected with said control knob for moving said tape at a relatively greater speed than the rim speed of said control knob.

ERIC H. LARSON.
